poration of New Jersey

Application December 17, 1935, Serial No. 54,858
In Great Britain January 1, 1935

22 Claims.

(Cl. 1—32)

This invention relates to machines for attaching heels to shoes, and especially to means for applying pressure to the work to resist the operating forces.

5 Machines for attaching heels to shoes are generally known either as inside heel-attaching machines or outside heel-attaching machines. In the former, heel-attaching fastenings are inserted from the inside of the shoe through the heel-seat into the heel, while in the latter, such fastenings are inserted from the outside through the heel and into the heel-seat.

10 In both kinds of machines, the shoe and heel are usually pressed firmly together before the heel-attaching fastenings are inserted and are so held during the insertion, and the present invention is chiefly concerned with providing in a heel-attaching machine simple and highly efficient mechanism, preferably including some such fluid 15 as oil, for obtaining the initial and continuing pressure.

15 The work-positioning and retaining mechanisms disclosed herein are made the subject of an application for Letters Patent of the United States in the name of Joseph Gouldbourn, filed 20 December 17, 1935, Serial No. 54,859.

25 The various objects and the several features of the present invention, in connection with either of the kinds of heel-attaching machines hereinbefore referred to, will become apparent from a 30 consideration of the following description, given by way of example, of a particular embodiment of the invention, which will be hereinafter illustratively described, with reference to the accompanying drawings, in connection with a heel-attaching machine of the general character of that disclosed in Letters Patent of the United States No. 1,195,134, Gouldbourn, August 15, 1916.

35 In the drawings,

40 Fig. 1 is a left-hand side elevation of the upper part of said patented heel-attaching machine, embodying this invention;

45 Fig. 2 is a side elevation, partly in section and to a larger scale, of the upper part of the machine shown in Fig. 1;

50 Fig. 3 is a front elevation, partly in section, of part of the pressure mechanism shown in Figs. 1 and 2;

55 Fig. 4 is a plan view of mechanism for positioning a shoe in the machine;

Fig. 5 is a section on the line V—V of Fig. 4, and

Fig. 6 is a section on the line VI—VI in Fig. 2.

The means for pressing a shoe and heel together and holding them so pressed while heel-

attaching fastenings are inserted may include a vertical plunger 1 (Fig. 2), which, at its lower end, supports work-pressing devices. The plunger is arranged to reciprocate in the machine-frame 3. It has at its rear side a vertical rack 5 engaged by a gear-segment 7 on the forward end of an arm 9 secured on a horizontal shaft 11 extending laterally of the machine and rotatable in the frame 3. The segment-arm 9 may be actuated to move the plunger downwardly by mechanism including a treadle 12 and other parts similar to those of the previously-mentioned patent, by which preliminary pressure is applied to the work, and the power-operation of the machine is initiated. Formed in the plunger 1 is 5 a cylindrical fluid-containing chamber 13, which is closed at its lower end and at its upper end is enlarged somewhat and is open. A cylindrical tube 15 is secured on the machine-frame by screws 17, 17 and extends downwardly into the chamber 13, the plunger 1 fitting and sliding about its exterior. Threaded into the tube 15 at its upper end is a spring-adjusting collar 19, having above the upper end of the tube a flange 21 in which are shown radial holes to receive a bar by which the collar 19 may be turned and adjusted longitudinally of the tube. The lower end of the tube has secured in it a valve member 23 having a vertical central bore 25 and between this and the outer wall of the member a number of smaller vertical bores. One of these smaller bores is shown at 27, opening through the top of the valve member 23 and into an enlarged portion 29 of the central bore 25 near but inside the lower end of the valve member. A valve-plate 31 is seated on the top of the member 23 and there normally closes the bores 27. This valve-plate is pressed down against the upper end of the valve member 23 by a coil-spring 33 confined in the tube 15 between the valve-plate and the collar 19. By 10 adjusting the collar, the pressure of the spring against the valve-plate and the resistance to movement of said plate may be varied.

Slidingly mounted in a bore in the spring-adjusting collar 19 and in the bore 25 in the valve member 23 is a tubular piston 35, which passes through the spring 33. This piston at its upper end is secured in a carrier 37 extending downwardly at the front of and partly around the upper portion of the machine-frame. At each side, the piston-carrier has formed in it horizontal grooves 39, which receive the forward rounded ends of arms 41 of a forked lever 43 by which the piston is moved up and down. The lever 43 is fulcrumed on a horizontal shaft 45 extend- 15 20 25 30 35 40 45 50 55

ing laterally of the machine and secured in the machine-frame. The rear end of the lever has pivotally connected to it the upper extremity of a downwardly-extending rod 47, which at its 5 lower end is connected to a crank-operated toggle 49, as in the Gouldbourn patent. When, during the power-operation of the machine, the toggle 10 is straightened, the piston 35 is moved down positively. This piston has extending axially through it a valve-rod 51, the lower end of which has secured on it a valve 53 arranged to close the lower opening of the bore 25 in the valve member 23, so that fluid in the bottom of the chamber 13 below the valve member is locked in said chamber. 15 The enlarged upper end 55 of the valve-rod 51 has a vertical slot which receives the rounded forward end 57 of a valve-operating lever 59 fulcrumed on a horizontal shaft 61 extending across the machine-frame. The valve-operating lever 20 59, at its rear extremity, is connected by a rod 63 to a lever 65 actuated in the operation of the machine, similarly to that in the previously-mentioned patent which effects the clamping engagement of the friction-plates.

25 The tube 15 has formed in it above the valve-plate 31, a number of openings 67, which allow fluid to pass from the enlarged portion of the chamber 13 in the plunger 1 into the inside of the tube. The top of the valve member 23 has 30 a number of recesses, one of which is shown at 69, formed in it between the bores 27 in the wall of the member. Through these recesses, fluid passing through a central opening in the valve-plate 31 surrounding the piston 35 can 35 flow through the bore 25 in the valve member 23 when the piston is raised. If the valve 53 at the bottom of the member is open, the fluid can pass into the bottom of the chamber 13 below the valve member.

40 When the machine is at rest, the plunger 1 is held in its raised position by a spring 70 acting upon the treadle mechanism. The piston 35 is raised so that its lower end is above the bottom of the recesses 69 in the valve member 23, 45 and the valve 53 at the bottom of the valve member is open. Consequently, the fluid can flow freely from the enlarged upper portion of the chamber 13 through the openings 67 in the tube 15, through the central opening in the valve-plate 31 and the recesses 69, and then down the bore 25 in said valve member and through the 50 open valve 53 into the bottom of the chamber 13. After a shoe and heel to be attached there-to have been positioned between a work-pressing post 185 carried at the bottom of the plunger 1 and a die-block 186 of the nailing mechanism of the machine, the plunger is lowered by the arm 9 and the treadle mechanism to apply 55 preliminary pressure to the work. During the lowering of the plunger, the fluid in the chamber 13 flows from the upper enlarged portion into the lower portion of said chamber. Continued depression of the treadle puts the machine into operation under power, as described in the 60 Gouldbourn patent, and during the power-cycle, the piston 35 is positively lowered by the toggle-lever 49. In its descent, the piston first closes the recesses 69 in the upper end of the valve member 23 and then forces, through the pressure 65 thus applied to the fluid in the chamber 13, the plunger 1 downwardly to urge the contact members on the post 185 against the work. When this travel of the plunger is stopped by the work, downward movement of the piston 35 70 forces the fluid in the bottom of the chamber 75

13 up through the holes 27 in the wall of the valve member 23 and past the valve-plate 31 on said member against the pressure of the spring 33. The amount of this final pressure applied to the work by the pressure devices is controlled by the spring 33, which may be adjusted by the collar 19 to vary its resistance and thus the force applied by the piston through the cylinder and its contained fluid, according to what is required by the character of the work. After the 10 downward stroke of the piston has been completed, the valve 53 is raised, by its connections to the lever 65, to close the opening at the bottom of the valve member 23. The fluid in the lower part of the chamber 13 is therefore locked therein and upward movement of the plunger 1 and the post 185 is prevented during the insertion of heel-attaching fastenings. After this, 15 by their operating mechanisms. If the treadle 20 has been released, the plunger is raised by a spring 72 associated with the treadle mechanism, the elements being thereby restored to their initial positions.

25 The means for positioning a shoe in relation to a heel which is to be attached thereto may include a band-clamp 71 (Fig. 4), which is arranged to engage the back and sides of the heel-end of the upper of the shoe and to enter the crease formed by the upper and outsole. This 30 band-clamp is preferably in the form of a strip of thin sheet-metal, bent to furnish opposite arms having substantially the shape of the heel-end of a shoe. The forward ends of the band-clamp have laterally extending ears 73, 73 pivotally connected to the forward ends of arms 75, 77 of a pair of levers which are fulcrumed at the rear on a vertical stud 79 secured in a horizontal slide 81 which is adjustable horizontally forwardly and rearwardly of the machine. 35 An ear 83 extends rearwardly from the band-clamp and is connected by a vertical pivot 85 to the band-clamp-slide 81. The band-clamp-levers 75 and 77 have, respectively, extending rearwardly and to the right from them, arms 40 87 and 89, carrying on vertical pivots cam-rolls 91, 93, respectively. These cam-rolls are respectively urged towards two cams 95 and 97 by a spring 99 connecting the arms 87, 89 of the band-clamp-levers. The cams are secured on a 45 vertical cam-shaft 101 rotatable in the slide 81 between the cam-rolls. When the cam-shaft is rotated in one direction, the forward ends of the band-clamp 71 are moved towards each other by the cams to grip and temporarily retain the 50 heel-end of a shoe. When the cam-shaft is rotated in the opposite direction, the spring 99 connecting the arms 87, 89 of the band-clamp-levers opens the clamp. From the cam-shaft 101 extends rearwardly an arm 103 having 55 rotatable in it a vertical pin 105. Through the pin is threaded a horizontal rod 107 having secured on its end toward the right of the machine a knurled collar 109 by which the rod 60 may be rotated.

65 The left-hand end of the rod 107 is threaded through a vertical pin 111 rotatable in a forwardly extending arm 113 of a bell-crank-lever 114 fulcrumed at 115 upon a vertical slide 117 movable on a guide 118, there being ball-bearings between the slide and guide. The threads on the rod 107 are right and left, so that if the rod is rotated a quick adjustment of the opposite sides of the band-clamp toward or from each other is obtained. The band-clamp-slide 81 is 70 75

adjustably mounted on a dovetailed guide 119 (Figs. 2 and 5) extending forwardly from the vertical slide 117. The guide 119 has formed on its upper surface rack-teeth 121, which are 5 engaged by the teeth of a pinion 123 on a horizontal shaft 125 rotatable in the slide 81. The right-hand end of the shaft 125 has secured on it a hand-lever 127 by which the shaft may be rotated to adjust the slide 81 and band-clamp 10 forwardly or rearwardly of the machine. The pointed end of a screw 129 threaded through the 15 slide engages a groove in the shaft 125 to prevent it from moving endwise. From the side of the band-clamp-slide 81 opposite the lever 127 projects a bolt 131 on which is slidably mounted a block 133, shaped as shown in Fig. 5, to engage the guide 119. This block is clamped against the guide 119, to hold the band-clamp 71 in adjusted position, by a nut or sleeve 135 threaded 20 on the bolt 131. The sleeve may be rotated by a hand-lever 137, so clamped upon it as to be adjustable into a convenient position for operation.

A second arm 139 of the bell-crank-lever 114 is connected by universal couplings and a rearwardly-extending rod 161 to an upwardly-extending arm 143 of a bell-crank-lever 145 fulcrumed on the machine-frame. The other arm 147 of the bell-crank-lever 145 is pivoted to the 25 upper end of one of a pair of toggle-links 149, 151. The lower end of the toggle-link 151 is connected to an arm 153 actuated through a link 152 from the treadle 12, as in the previously-mentioned patent. The toggle 149, 151 is normally maintained partly broken by the engagement of stop-lugs 155, 155 on the toggle-links close to their common connection, which lugs are held in normal engagement by a spring 157 connected to the toggle and to the frame of the 30 machine. Normally, the opposite sides of the band-clamp 71 are separated by the spring 99. When the treadle is depressed to move the work-pressing members downwardly, the first part of the movement causes, through the chain of connections between the arm 153 and the cam-shaft 101, the band-clamp-cams 95, 97 to be rotated to close the sides of the band-clamp 71 against a shoe placed between them. Thereafter, during continued depression of the treadle, the 35 toggle-links 149, 151 break further, and, while the contact devices on the post 185 are actuated by the treadle to press the work, the spring 157 connected to the toggle yields and holds the cams 95, 97 in the positions they reached when moving the band-clamp into engagement with the shoe. When the treadle is released and as it is 40 fully raised by its spring, the spring 157 returns the toggle-links 149, 151 to their partly broken condition, and thereafter the cams are rotated, 45 and the clamp 71 is again opened by the spring 99.

If the machine is being used for attaching a heel or heel-base to a shoe by fastenings inserted from the outside and for spanking a top-lift 45 thereon in successive operating cycles without removing the shoe from the machine, it is desirable, to avoid the opening of the band-clamp 71 between the successive cycles and the releasing 50 thereby of the shoe, to prevent the treadle 70 from being raised to its highest position. For this purpose, a rod 161 (Fig. 1) joining the treadle-actuated lever 153 to the work-pressing devices, as in the Gouldbourn patent, has secured on it a block 163. A star-wheel 165 having six 55 radial arms is rotatably mounted on a horizontal

stud, projecting from the machine-frame below the block 163 and between the rod 161 and the frame of the machine. During each cycle of the machine, the star-wheel is rotated to bring either the end of one of the arms or a gap between the 5 arms beneath the block 163. When one of the arms is beneath the block, and the rod 161 is lowered as the treadle is raised by its spring, said block engages the arm, and the band-clamp is stopped before it reaches its fully raised position and is opened. If a gap between the arms of the star-wheel 165 is below the block 163, the band-clamp will be fully raised and opened when the treadle is released. The star-wheel has secured on it a ratchet-wheel 167, which is 10 engaged and rotated by a pawl 169 carried by a ratchet-lever 171 fulcrumed on the machine-frame and urged towards the ratchet-wheel by a spring 172. The ratchet-lever is connected by a link 173 to the lever 65, hereinbefore referred to 15 as operating the valve 53 in the work-pressing mechanism, so that during each cycle of the machine, the ratchet-wheel is rotated a distance to present to the block 163 either one of the arms on the star-wheel 165 or a gap between the arms. 20 The pawl 169 may, by means of a pin 175 inserted in a hole 177 in the lever and engaging said pawl, be held out of engagement with the ratchet-wheel if the machine is used for attaching heels without top-lift-spanking. This allows 25 a gap between the star-wheel-arms to be constantly aligned with the block, so that the band-clamp will be fully raised and opened each time the machine is stopped.

The work-pressing devices carried by the 30 plunger 1 include, as applied to a machine of the outside heel-attaching kind, a member for engaging the crown or top of the cone of a last in the shoe and side members for engaging the upper of the shoe at each side of the heel-end 40 above the band-clamp and between the top and bottom of the last. The side members assist in pressing the shoe against the heel and the heel against the top-lift, if a top-lift is being spanked on to the heel, and prevent lateral tipping of the 45 last and shoe when pressure is applied to the work. This tipping is especially liable to occur if the top of the last is worn or crushed.

The member which engages the crown of the last is a plate 181 (Figs. 2 and 3), which may or 50 may not have a last-pin extending downwardly from it, depending upon the character of the shoe being operated upon. The plate is mounted on the underside of a block 183 for limited movement laterally of the shoe. The block is carried by the lower end of the post 185 and is arranged to tip about an axis lying in the underside of the plate 181 and close to the last-pin, if such is provided, so that the plate 181 and block 183 can tip lengthwise of the shoe. The block 55 has formed on it an arcuate gear-segment 187, and the post has rotatably mounted in it a shaft 189 on which is a spiral gear 191 meshing with the segment. The shaft may be rotated by a knurled head 193 on its forward end to adjust the 60 angle of the plate 181, and the shaft may be locked in adjusted position by a plunger and notches in the shaft (not shown). The post 185 is pivotally mounted on a horizontal shaft 195 extending laterally of the machine and secured 65 in a slide 197 mounted for fore-and-aft movement in a guideway formed in the underside of a plate 199 on the lower end of a carrier-sleeve 201 surrounding the lower end of the plunger 1 and arranged to move to a limited extent longi- 70 75

tudinally thereof. At the inner side of the post 185 is a rearwardly-extending arm 203 which at its end curves upwardly and forwardly and has formed in it a slot 205 which, when the post is in operating position, first lies horizontally and then curves upwardly at its rear, generally concentric to the shaft 195. A roll 207 is rotatable on the plate 199 in the slot 205. When the post 185 and slide 197 are pulled forward by the operator, the slot travels along the roll 207 until the curved part reaches said roll, when forward movement of the slide ceases and the post may be tipped on its pivot 195 forward and up, until the upper end of the curved part of the slot engages the roll. The post is then in a convenient position for the withdrawal of the work and the applying of fresh work. When in its forward and raised position, the post is locked to the slide by a pin 209 in said post, which engages a spring-plunger 211 in the slide.

Connected to the slide 197 is a link 213, which at its lower end is joined to the vertical slide 117 which carries the band-clamp-slide 81, so that the band-clamp 71 moves up and down with the slide 197. The link 213 is threaded through pins 215, 217 rotatable respectively in the slide 117 and in a lever 219 fulcrumed on the slide 197 and having a forked forward end engaged by a pin 221 in the post 185. The link 213 has right and left screw-threads on its opposite ends, so that by rotating the link the vertical slide 117, and with it the band-clamp, may be adjusted up or down relatively to the post to cause said band-clamp to be properly positioned to receive the heel-end of a shoe. When the slide 197 is moved forward and the post 185 is swung up, the pin 221 turns the lever 219 in a clockwise direction, as viewed in Fig. 2. The link is therefore actuated to draw up the band-clamp further than it has already been raised as the slide 197 and band-clamp were elevated by the plunger 1 upon release of the treadle. This provides additional clearance for the presentation of a heel and top-lift to the machine.

45 The members which engage the upper at opposite sides of the heel-end of the shoe consist of two leather-faced blocks 223, 223 (Fig. 3), which are mounted for limited rocking movement lengthwise and heightwise of the shoe on the lower ends of upwardly and outwardly curved bars 225, 225, adjustably held in the lower ends of upwardly-extending clamp-levers 227, 227 situated on opposite sides of the post 185. The clamp-levers are fulcrumed on horizontal pivots 229, 229 secured in the outer extremities of a pair of lever-carrying arms 231, 231. These arms 231 are fixed at their opposite ends to horizontal studs 233, 233 rotatable in lugs extending laterally from the sleeve 201 of the work-pressing mechanism.

60 The pivots 233, 233 of the lever-carrying arms are on opposite sides of the vertical axis of the plunger 1, and the pivot 229 of each clamp-lever 227 at the outer end of its arm is on the opposite side of said axis from the pivot of the arm. The 65 lever-carrying arms 231, 231 thus cross each other, passing through vertical openings extending laterally through the sleeve 201 and plunger 1. The clamp-levers at their upper ends are guided in vertical grooves 235, 235 formed in blocks 237, 237 secured to the machine-frame. The sides of the grooves prevent fore-and-aft springing of the levers, which, at their upper ends, carry cam-rolls 239, 239 held against the bottoms of the grooves by a spring 241 uniting the levers. The 75 upper edge of each of the lever-carrying arms

has formed in it a curved recess which is comparatively close to the pivot 233 of the arm and is engaged by a rounded end of an actuating lever 243 pivoted in the opening in the plunger 1 through which the lever-carrying arms pass. The upper edge of the actuating lever 243, the rounded ends of which are of comparatively short radius from the pivot of the lever, is curved about a horizontal axis extending forwardly and rearwardly of the machine and passing through the 10 vertical axis of the plunger 1. The curved edge of the actuating lever seats in a correspondingly curved recess 245 formed in the upper wall of the opening in the plunger through which the lever-carrying arms pass. A pin 247 in the plunger, which passes through a hole in the actuating lever larger than the pin, allows said lever to rock but prevents it from falling if the lever-carrying arms are removed. These arms are normally raised by a spring 249 connected to pins extending 20 downwardly from the arms at their pivots.

The plunger-sleeve 201 has rotatably mounted in it a horizontal pin 251 (Fig. 2) secured by a screw 253. The pin extends from the front of the sleeve toward the rear and at its outer end has a squared portion by which it may be rotated. The inner end of the pin has an eccentric portion 255 which enters a hole 257 in the plunger of greater diameter than the eccentric portion. With the plunger 1 in its raised position, the portion 255 of the pin engages the lower wall of the hole, and the sleeve 201 and parts carried by it are thereby suspended. When a shoe on the post has been swung downwardly and moved back to position the shoe in the band-clamp 71, the blocks 223 are preferably comparatively close to the upper so that the operator's fingers cannot accidentally be caught between the shoe and blocks when the latter are actuated.

When the plunger 1 is depressed by the treadle 12, the plate 181 and the blocks 223 move down together with the shoe until the heel-seat engages a heel supported upon the die-block 186. Thereafter, during continued downward movement of the plunger 1, the plate 181 is arrested, and the 45 actuating lever 243, depressed by the plunger-surface 245, swings the lever-carrying arms 231 downwardly about their pivotal axes to move the levers 227 and cause their blocks 223 to engage the shoe. At this time, the lower wall of the 50 hole 257 in the plunger moves away from the eccentric-portion 255 of the pin 251 in the sleeve 201. By adjustment of the eccentric 255, the initial spacing of the arms 231 from the lever 243 and consequently the extent of clamping movement of the blocks 223 may be varied. Owing to the arcuate movement of the fulcra of the clamp-levers 227 on the lever-carrying arms 231, and the vertical movement of the upper ends of the clamp-levers by reason of their guidance by 60 the frame-blocks 237, the clamping blocks 223 are moved towards the shoe in a path approximately at right angles to the faces of the upper which they engage. Consequently, they do not scrape over and mar the upper-material. The 65 pivotal mounting of the actuating lever 243 in the plunger allows the blocks 223 to accommodate themselves to the position of the sides of the heel-end of the shoe laterally of the machine. When the plunger 1 is moved down to apply 70 pressure to the work, and the plate 181 and blocks 223 are depressed by the actuating lever, the pressure of the blocks against the shoe is equalized by tipping of the actuating lever. Owing to the recesses in the lever-carrying arms 231 75

being comparatively close to the pivots of the arms as compared with the fulcra 229 of the levers 227 at the ends of the arms, the pressure of the plate 181 against the last is greater than 5 the pressure of the blocks 223 against the upper.

If a low shoe rather than a high shoe is being operated upon, a last-pin in the plate 181 may be dispensed with, and the post need not, unless desired, be moved upon the plunger 1 to introduce 10 a shoe into the machine or to remove it therefrom, since the last will project above the upper. Consequently, the shoe and last can be presented to the band-clamp by passing the rear portions under the plate. In this case, the additional 15 raising of the band-clamp by the lever 219 will not occur, its elevation when the treadle is released allowing the introduction and removal of the work.

Having described our invention, what we claim 20 as new and desire to secure by Letters Patent of the United States is:

1. In a heel-attaching machine, relatively movable work-contacting members, relatively movable actuating members therefor comprising a 25 cylinder and a co-operating piston, one of the actuating members being joined to one of the work-contacting members to effect its movement, and means for moving one of the actuating members relatively to the other actuating member to 30 create pressure in the cylinder during the application of final pressure to the work.

2. In a heel-attaching machine, relatively movable work-contacting members, relatively movable actuating members therefor comprising a 35 cylinder and a co-operating piston, means arranged to move the cylinder to apply preliminary pressure to the work, and means for moving the piston within the cylinder while producing further pressure-movement of the cylinder.

40 3. In a heel-attaching machine, relatively movable work-contacting members, relatively movable actuating members therefor comprising a cylinder and a co-operating piston, one of the actuating members being joined to one of the 45 work-contacting members to effect its movement, means for moving the other actuating member to create pressure in the cylinder during the relative movement of said members, and means arranged to control the degree of the thus-generated pressure. 50

4. In a heel-attaching machine, relatively movable work-contacting members, relatively movable actuating members therefor comprising a fluid-containing cylinder and a co-operating piston, one of the actuating members being joined to one of the work-contacting members to effect its movement, means for moving the other actuating member to create pressure in the fluid in the cylinder during the relative movement of said 55 members and apply such pressure to the work, and means for preventing the escape of the fluid under pressure in the cylinder to retain the work under pressure.

5. In a heel-attaching machine, relatively movable work-contacting members, relatively movable actuating members therefor comprising a cylinder and a co-operating piston, one of the actuating members being movable by the operator, and means made effective under the power 60 of the machine for moving the other actuating member to create pressure in the cylinder during the relative movement of said members.

6. In a heel-attaching machine, relatively movable work-contacting members, relatively movable actuating members therefor comprising a 65

fluid-containing cylinder and a co-operating piston, one of the actuating members being movable by the operator, means made effective under the power of the machine for moving the other actuating member to create pressure in the fluid in the cylinder during the relative movement of said members and apply such pressure to the work, and means made effective under the power of the machine for preventing escape of the fluid under pressure in the cylinder to retain the work under pressure. 10

7. In a heel-attaching machine, relatively movable work-contacting members, relatively movable actuating members therefor comprising a cylinder and a co-operating piston, one of the actuating members being joined to one of the work-contacting members to effect its movement, and a valve member supported within the cylinder and through a passage in which the piston operates. 20

8. In a heel-attaching machine, relatively movable work-contacting members, relatively movable actuating members therefor comprising a fluid-containing cylinder and a co-operating piston, one of the actuating members being joined to one of the work-contacting members to effect its movement, a valve member supported within the cylinder, said valve member having an opening, and a valve movable under the influence of the fluid to control the flow of said fluid through the 30 opening.

9. In a heel-attaching machine, relatively movable work-contacting members, relatively movable actuating members therefor comprising a fluid-containing cylinder and a co-operating piston, one of the actuating members being joined to one of the work-contacting members to effect its movement, a valve member supported within the cylinder, said valve member having an opening, a valve movable under the influence of the 35 fluid to control the flow of said fluid through the opening, and means arranged to vary the resistance of the valve to movement.

10. In a heel-attaching machine, relatively movable work-contacting members, relatively movable actuating members therefor comprising a cylinder and a co-operating piston, one of the actuating members being joined to one of the work-contacting members to effect its movement, and a valve member supported within the cylinder 40 and through which the piston operates, said valve member having an opening controlled by the piston. 50

11. In a heel-attaching machine, relatively movable work-contacting members, relatively movable actuating members therefor comprising a fluid-containing cylinder and a co-operating piston, one of the actuating members being joined to one of the work-contacting members to effect its movement, a valve member supported within the cylinder, said valve member being provided with an opening, and a valve movable under the power of the machine to control the passage of fluid through the opening. 55

12. In a heel-attaching machine, relatively movable work-contacting members, relatively movable actuating members therefor comprising a fluid-containing cylinder and a co-operating piston, one of the actuating members being joined to one of the work-contacting members to effect 60 its movement, a valve member supported within the cylinder, said valve member being provided with a plurality of openings, a valve movable under the influence of the fluid to control the passage of said fluid through one of the openings. 70 75

and a valve movable under the power of the machine to control the passage of the fluid through another opening.

13. In a heel-attaching machine, relatively 5 movable work-contacting members, relatively movable actuating members therefor comprising a cylinder and a co-operating piston, one of the actuating members being joined to one of the work-contacting members to effect its movement, 10 a valve member supported within the cylinder, said valve member being provided with openings, a plurality of valves to control certain of the openings, and another opening controlled by the piston.

14. In a heel-attaching machine, a frame, a cylinder movable therein and carrying a work-pressing member, a tube fixed to the frame and fitting within the cylinder, a piston movable through the tube, and means for reciprocating 20 the piston.

15. In a heel-attaching machine, a frame, a cylinder movable by the operator therein and carrying a work-pressing member, a tube fixed to the frame and fitting within the cylinder, a piston movable through the tube, and means for reciprocating the piston under the power of the machine.

16. In a heel-attaching machine, a frame, a cylinder movable therein and carrying a work-pressing member, a tube fitting within the cylinder, there being openings in the wall of the tube to connect upper and lower portions of the cylinder, a piston movable through the tube, and means for reciprocating the piston.

17. In a heel-attaching machine, a frame, a cylinder movable therein and carrying a work-pressing member, a tube fitting within the cylinder, a piston movable through the tube, means for reciprocating the piston, and a valve member 40 mounted at the inner extremity of the tube.

18. In a heel-attaching machine, a frame, a cylinder movable therein and carrying a work-pressing member, a tube fitting within the cylinder, a piston movable through the tube, means for reciprocating the piston, and a valve member 45

mounted at the inner extremity of the tube and having openings controlled by the piston in its movement.

19. In a heel-attaching machine, a frame, a cylinder movable therein and carrying a work-pressing member, a tube fixed to the frame and fitting within the cylinder, a piston movable through the tube, means for reciprocating the piston, a valve member mounted at the inner extremity of the tube and having a passage opening through its opposite ends, and a valve for controlling the passage. 5 10

20. In a heel-attaching machine, a frame, a cylinder movable therein and carrying a work-pressing member, a tube fixed to the frame and fitting within the cylinder, a piston movable through the tube, means for reciprocating the piston, a valve member mounted at the inner extremity of the tube and having a passage opening through its opposite ends, a valve for controlling the passage, and means for moving the valve under the power of the machine. 15 20

21. In a heel-attaching machine, a frame, a cylinder movable therein and carrying a work-pressing member, a tube fixed to the frame and fitting within the cylinder, a piston movable through the tube, means for reciprocating the piston, a valve member mounted at the inner extremity of the tube and having a passage opening through its opposite end, a valve for controlling the passage, a spring within the tube acting to normally close the valve, and means movable upon the tube for varying the force of the spring. 25 30

22. In a heel-attaching machine, a frame, a cylinder movable therein and carrying a work-pressing member, a tube fixed to the frame and fitting within the cylinder, a tubular piston movable through the tube, means for reciprocating the piston, a valve member mounted at the inner extremity of the tube, a valve-rod movable 40 through the piston, and a valve carried by the rod and co-operating with the valve member. 35
